LOW FREQUENCY TRANSFORMER

Joseph Poliakoff, London, England, assignor to
Multitone Electric Company Limited, London,
England

Application June 13, 1932, Serial No. 616,982
In Great Britain June 26, 1931

2 Claims. (Cl. 178—44)

The present invention relates to improvements in audio frequency transformers and transformer circuits, such as intervalve transformers and coupling transformers between gramophone pick-ups, microphones and the like and grid circuits of valves, used in wired and wireless telephony, as well as in various sound reproducing apparatus such as talking film apparatus, public address systems, electrically reproducing gramophones, 10 for amplifiers in aids for deafness apparatus and for like purposes.

This invention consists in the construction of audio frequency transformers in such a way that the frequency-amplification curve of the transformer can be given the most advantageous shape 15 for the particular working conditions, considering the whole apparatus in which the transformer is included.

It has hitherto been proposed to place resistances, inductances and condensers in the primary, secondary or tertiary circuits of individual electric transformers, for purposes of increasing stability of working, obtaining greater uniformity of amplification, suppression or production of 20 resonances and for other purposes.

My invention provides for a complete and continuous control of the shape of the response curve of transformer and transformer circuits, allowing it to have practically any shape and tilt up or down, it being sufficient to employ only the secondary and primary windings of the transformer.

According to this invention, wherein a secondary circuit divided into two or more parts connected in series and mounted on the same core is employed, the control of the response curve of the transformer is effected by constructing such parts, which may act either to assist one another or differentially, in such a manner as to give them frequency-amplification curves of different characteristics, means being provided to control the frequency amplification curves to be varied to suit changing conditions of working of the apparatus and varying requirements.

Such differences in the characteristic curves are obtained either by having an unequal number of turns in such parts of the secondary circuit and/or by the employment of resistive and/or capacitative shunts.

The invention provides methods of summing the effects of the various parts in such a way that the resultant curve can be given any shape from a sharply falling curve through a substantially straight line to a curve having a steeply rising characteristic, as well as looped curves.

Referring to the drawings, Fig. 1 shows a transformer circuit according to my invention.

In Figs. 2 through 6, a different modification is shown for each figure.

Figs. 4a, 5a, and 6a are diagrams representing

the operation of the circuits of Figs. 4, 5 and 6, respectively.

Figure 1 shows the primary and secondary windings of a transformer with a secondary divided into two parts s' , s'' , of which the part s' is shown shunted by a condenser c in series with a resistance r . The primary coil is marked p .

One of the secondary terminals is connected to the movable member a of a potential divider, the resistance r' of which is connected in parallel with part s' of the divided secondary.

According to my invention the circuits will yield a large number of curves of various shapes by choosing the constants in such a way that coils s' and s'' have different characteristics, that is, 15 transformers formed of p and s' alone and p and s'' alone would have different frequency amplification curves.

A transformer has been constructed for instance, with the following constants giving a curve 20 showing maxima both in the low and high frequency ends of the working acoustic scale, such a curve being suitable for the compensation of the attenuation of the ends of the scale in reproducing broadcast and recorded music and speech.

Constants

p =4000 turns.

Inductance of p =81 henries, wound with 44 30

S. W. G. wire.

Resistance of p =1200 ohms.

s' =12000 turns.

Resistance of s'' =7000 ohms, wound with 46

S. W. G. wire.

35

Inductance of s'' =729 henries.

s'' =17000 turns, wound with 47

S. W. G. wire.

Inductance of s'' =1462 henries.

Resistance of s'' =20000 ohms.

40

c =.003 microfarads.

r =0.

Coils s' , p and s'' were wound on separate bobbins placed on the central limb of a three limb closed magnetic circuit core consisting of thin laminations of nickel-iron alloy.

The s' coil is made to resonate with the shunt capacity c and its distributed capacity at the low frequency end of the acoustic scale and has a 45 progressively falling curve, while the s'' coil has a substantially straight curve except for a sharp resonance in the high frequency (4000) part of the acoustic range.

When the two coils are connected in series, a 50 curve with two maxima is produced. If instead two similar coils of 14,500 turns are connected in series, the high frequency end of the scale will be attenuated, for the high frequency resonance will occur at about 2000~ and there will be a 55 60

serious drop in amplification with signals of 4000~ and over.

Further the low frequency end of the scale can be effectively controlled so as to permit change 5 from a looped to a rising curve by means of the potential divider connected across the s' coil as shown in Figure 1. The motion of the moving member a "mixes" the contributions of coils s'' and s' in different proportions. When the moving member a is at the extreme right a sharply rising curve is obtained, since the s' coil contributes nothing to the resultant curve, but greatly reduces the low frequency component contributed by the s'' coil, leaving the high frequency 10 unaffected.

As the movable member travels to the left the low frequency end of the curve is progressively raised right up to the maximum.

Thus means are provided for changing a looped 20 curve to a rising curve or any curve intermediate between a looped and rising curve.

The circuit in Figure 2 shows the secondary made in two parts s' , s'' across the ends of which there are connected two condensers c' , c'' having the resistance r' of a potential divider connected between them, the movable member a' of which is connected to the junction between the two parts of the secondary. Each of such parts can be made to resonate with the condensers c' and c'' in turn by sliding the contact a' attached to their junction towards c' or c'' . The resistance r'' joining the two condensers can be made high enough to damp out the resonance of the whole 30 of the secondary with the two condensers in series or it may be made low enough to preserve it at any desired magnitude.

This circuit enables amplification of either end 40 of the acoustic scale or any other part thereof to be raised above that of the rest of the scale, but does not enable either end to be depressed below the average amplification level.

Figure 3 shows a circuit which is identical 45 with that of Figure 2 except that one of the condensers, c'' , is dispensed with. By this means a circuit is obtained capable of boosting up either end or any other part of the curve and depressing the part corresponding to low and middle frequencies to any desired low level.

As the movable member a' moves towards the 50 condenser c' greater and sharper resonance is produced (in the low frequency end or any other point of the curve) while motion to the right will reduce the resistance across the untuned coil and thus drop the impedance of all the windings on the core producing decreased magnification of the low and middle frequencies.

It has been found that with comparatively large 60 secondaries of 16,000 turns or more, the placing of resistance across a portion thereof tends to raise the amplification given to the high frequencies, which effect generally increased with decreasing resistance.

When the connections of the movable member a' the potential divider and of the end of the 65 resistance r'' connected to the end of the part s'' of the secondary (Figure 3) are interchanged, as shown in Figure 4, a complete control of the curve is obtained as shown on the curve, Figure 70 4a. The motion of the movable member a' changes the sharply falling curve I having a boost at the low frequencies, through a comparatively straight line curve II to a sharply rising curve III with a maximum at 3000~.

If the connections of the movable member a' 75

and the outer end of the condenser c'' (Figure 2) are reversed the circuit obtained is as shown in Figure 4 including the dotted condenser c'' .

As the movable member a' travels to the left the whole of the secondary resonates with c' giving a low frequency boost and a falling curve. When the direction of motion of the member a' is reversed, the coil s'' begins to resonate with the condenser c'' . The frequency of the resonance can be conveniently fixed in the high frequencies, 10 so that any curve intermediate between a sharply falling curve with a low frequency boost to a straight line curve with a boost at the high frequency end is available.

In both circuits of Figure 4 additional curve 15 adjustment may be provided by winding the part s'' in the opposite sense to the part s' .

This reversal is useful mainly for the purpose of providing a curve with an adjustable boost in the low frequency part and a falling curve adjustable to a substantially straight curve without peaks in the high frequency part.

The low frequency boost is produced by resonance of the whole secondary with condenser c' while the high frequency peak due to the distributed capacity of s' is taken off by making s'' and c'' resonate at the frequency of the peak, which depresses the peak owing to the differential action of s' and s'' .

Figure 5 shows another form of the transformer, wherein the sectional coil s'' is wound differentially as shown or it may be wound in the same sense, with respect to the coil s' . The low frequency boost and the falling curve are here produced by means of a condenser c''' , one end 30 of which is connected to one end of the primary winding p , its other end being connected to one end of the potential divider r , the movable member a of which is connected to the outer end of the coil s'' and the other end to the junction of the coils s' and s'' . In this circuit the free end of the coil s' is connected to the grid G of the valve, the free end of the other secondary coil s'' being connected to the grid bias $G.B.$ whilst the end of the primary coil p to which the condenser c''' is connected, is itself connected to the plate P of the valve. The other end of the primary circuit is connected to the +H.T. (i. e. the positive of the battery or other source of electric pressure) or to the grid bias, $G.B.$, if the transformer is "resistance fed".

The operation of this circuit obviously depends on the existence of a low impedance path between the $G.B.$ end of the secondary and the +H.T. end of the primary. Consequently this 55 circuit can only be used for intervalve coupling, its use for other purposes being possible only if is operated as an auto-transformer.

Figure 5a shows three overall amplification curves of a 2-valve audio frequency amplifier, 60 the two valves being coupled by a transformer constructed as shown in Figure 5.

The constants of the transformer were:—

Primary turns=4000 wound with 44 S. W. G.

$s' = 21000$ wound with 46 S. W. G.
Secondary turns $s'' = 3500$ wound with 46 S. W. G.
 $c = .025$ micro-farads.

The figure shows that a very complete control 70 of the overall curve is provided by this circuit. When the movable member a is in its lowest position, the falling curve I is obtained, an intermediate position of the member a yields the substantially straight line curve II and the upper- 75

most position of the member a yields the rising curve III.

For many purposes, such as correcting the attenuation in the high frequencies of the acoustic scale produced by broadcast receivers with very sharp tuning, it has been found advantageous to build transformers in which the low and middle frequencies can be depressed to any desired level without appreciably affecting the high frequencies.

The circuit illustrated in Figure 6 gives the desired variation in response curves. The secondary consists of two equal or unequal coils s' and s'' , s' being shunted by a high resistance r , which forms the resistance of the potential divider, one end of s'' going to the G or G. B. of the next valve, and the other end to the movable member a of the potential divider.

The motion of the slider has been found to control the amplification of low and middle frequencies without affecting appreciably the high frequencies.

The three curves in Figure 6a have been taken of a transformer according to Figure 6 with the following constants:

Primary coil=4000 turns wound with 44 S. W. G. wire.

Coil s' =17,000 turns wound with 47 S. W. G. wire.

Coil s'' =17,000 turns wound with 47 S. W. G. wire.

Potential divider 0.5 megohm.

Curve I is obtained when the movable contact a is in its extreme left hand position, Curve II in an intermediate position, and Curve III when in its extreme right-hand position.

It has been found advantageous to form some of the capacities used in the several circuits above described by bifilar winding on the cores of the transformers, which when inductive pro-

vide additional means of curve control. The wire could if desired, be replaced by suitably insulated metal strips.

In all the above circuits the continuously variable potential dividers may be replaced by fixed potential dividers, or the variation can be effected by means of tappings and a suitable switch.

In all figures, except Figure 5, the secondaries and primaries can be connected either way round with respect to the valves or circuits they couple.

Hereinabove I have spoken of division of the secondary into two or more parts, the word division is to be understood in the electrical sense and not necessarily in the mechanical sense, since it may be effected e. g. by providing a tapping in a single coil.

I claim:

1. An audio frequency transformer for inter-valve coupling, or for coupling pick-ups, microphones, photocells and the like to grid circuits of valves with a secondary divided into two parts connected in series, a shunt to one of said parts of the secondary, said shunt comprising a condenser and the resistance of a potential divider connected in series, the movable member of the potential divider being connected to the outer terminal of the other part of the secondary.

2. An audio frequency transformer for inter-valve coupling, or for coupling pick-ups, microphones, photocells, and the like to grid circuits of valves with a secondary divided into two parts arranged on the same core and connected so as to act in opposition to one another, one of said parts of the secondary being shunted by the resistance of a potential divider, the movable member of which is connected to one end of the other part of the secondary.

JOSEPH POLIAKOFF. 40
